UNITED STATES PATENT OFFICE

150,766

DESIGN FOR A FLOAT FOR BAR SOAP
OR THE LIKE

Ferdinand A. Hilenski, Salem, Mass.

Application October 25, 1946, Serial No. 134,262

Term of patent 3½ years

(Cl. D4—3)

To all whom it may concern:

Be it known that I, Ferdinand A. Hilenski, a citizen of the United States, residing at Salem, in the county of Essex and State of Massachusetts, have invented a new, original, and ornamental Design for a Float for Bar Soap or the like, of which the following is a specification, reference being had to the accompanying drawing, forming a part thereof in which,

Figure 1 is a top plan view of a float for bar soap or the like showing my new design.

Figure 2 is a view partly in vertical section on the line 2—2 of Figure 1 and partly in side elevation.

I claim:

The ornamental design for a float for bar soap or the like, as shown.

FERDINAND A. HILENSKI.
